UNITED STATES PATENT OFFICE.

AMBROSE L. MOORE AND GEORGE D. MOORE, OF NEW ORLEANS, LOUISIANA.

EXCELSIOR-MACHINE.

SPECIFICATION forming part of Letters Patent No. 436,255, dated September 9, 1890.

Application filed February 20, 1890. Serial No. 341,181. (No model.)

To all whom it may concern:

Be it known that we, AMBROSE L. MOORE and GEORGE D. MOORE, of New Orleans, in the parish of Orleans and State of Louisiana, 5 have invented a new and Improved Excelsior-Machine, of which the following is a full, clear, and exact description.

The invention relates to wood-working machinery for manufacturing excelsior from 10 blocks of wood.

The object of the invention is to provide a new and improved excelsior-machine, which is simple and durable in construction and very effective in operation, and cuts a series 15 of shavings on both the forward and backward stroke of the knife-head.

The invention consists in certain parts and details and combinations of the same, as will be described hereinafter, and then pointed 20 out in the claims.

Reference is to be had to the accompanying drawings, forming a part of this specification, in which similar letters of reference indicate corresponding parts in all the figures.

25 Figure 1 is a plan view of the improvement. Fig. 2 is a longitudinal sectional elevation of the same. Fig. 3 is an inverted plan view of the same. Fig. 4 is a side elevation of the shaft for changing one feed-roller. Fig. 5 is 30 a side elevation of the feed-roller pin, and Fig. 6 is an enlarged sectional side elevation of the mechanism for imparting motion to the feed-rollers.

The improved excelsior-machine A is provided with a suitably-constructed frame B, in which is held to slide in suitable guideways a knife-head C, pivotally connected at one end with a pitman D, pivoted on a crank-wheel E, secured on the main driving shaft F, which 40 when rotated imparts a reciprocating motion by means of the crank-wheel E and the pitman D to the knife-head C. Other suitable means may be employed to impart a reciprocating motion to the knife-head C.

45 In said knife-head C are arranged the transversely-extending slots G, G', and G'', of which the slot G'' is located between the slots G and G', and the three slots are arranged parallel with each other, as shown in Fig. 3.

50 In the slots G and G' extend the cutting-edges of the knives H and H', respectively,

extending on the under side of the knife-head C, and provided with the eyes H², through which passes a shaft I or I', respectively, held in suitable bearings formed on the under side 55 of the knife-head C. The knives H and H' are inclined in opposite directions from each other, as is plainly shown in Figs. 2 and 3, the said knives swinging on their shafts I and I' as a fulcrum.

From one of the eyes H² of the knives H and H' extend outward arms J and J', respectively, pressed downward by springs K and K', respectively, located between the under side of the knife-head C, and the tops of 65 the arms J and J', respectively, being coiled on pins K², secured to the under side of the knife-head C and projecting through suitable apertures in the arms J and J' to form guides for the same.

In the knife-head C screw the screws L and L', respectively, adapted to engage with their lower ends the tops of the knives H and H', respectively, the said screws serving to regulate the thickness of the shaving to be cut.

In the middle slot G² are arranged a series of rotary cutter-disks N, held on a shaft N', mounted in suitable bearings in the cutter-head C. The upper edges of the cutter-disks N project above the top of the knife-head C, 80 and are adapted to make longitudinal cuts into the under side of the block of wood, so as to cut the shavings into strips.

On the top of the knife-head C are arranged the transversely-extending feed-rollers O and O', each provided with a series of lugs or projections O², adapted to engage the ends of the block of wood P, so as to hold the latter in place, and when the feed-rollers are rotated toward each other to feed the block of 90 wood P downward onto the top of the knife-head C. The feed-rollers O and O' are secured on shafts O³ and O⁴, respectively, carrying at one outer end the worm-wheels Q and Q', respectively, meshing in worms Q² 95 and Q³, respectively, secured on a longitudinally-extending shaft Q⁴, mounted to turn in suitable bearings on the top of the main frame B.

On one end of the shaft Q⁴ is secured a 100 bevel gear-wheel Q⁵, in mesh with a bevel gear-wheel Q⁶, secured on a short trans-

versely-extending shaft R, mounted to turn in suitable bearings on the frame B.

On the inner end of the shaft R is secured a ratchet-wheel R', (see Figs. 1, 3, and 6,) 5 adapted to be engaged by a spring-pawl S, pivoted to an arm S', fulcrumed on the shaft R. The inner end of the arm S' is adapted to be engaged by a block S², having a beveled edge and secured on one end of the knife-head C. When the arm S' is not engaged by the said block S², its outer end butts on a lug or bracket S³, held vertically adjustable on the frame B. When the cutter-head C moves toward the driving-shaft F, the block S² 10 engages and raises the inner end of the arm S', so that the spring-pawl S, hung on the said arm S', swings downward and turns the ratchet-wheel R', whereby the shafts R and Q⁴ are set in motion, and the shaft Q⁴, by its worms Q² and Q³, engaging the worm-wheels Q and Q', turns the feed-roller shafts O³ and O⁴, carrying the feed-rollers O and O', so that 15 the latter feed the block P downward onto the top of the knife-head C.

25 In order to readily insert the block of wood P between the rollers O and O', the bearings T of the feed-roller O' are rigidly secured on the top of the main frame B, while the bearings T' of the feed-roller O are held to slide 30 longitudinally in suitable guideways on the frame B.

35 In each of the bearings T' of the feed-roller O is secured a pin U, provided with two collars U', engaged by sets of lugs V', projecting from a shaft V, mounted to turn in suitable bearings on top of the main frame B. On one outer end of this shaft V is secured a handle V², for conveniently turning the said shaft V, so that the latter, by its lugs V' pressing on 40 the collars U' of the two pins U, slide the latter to move the bearings T' toward or from the bearings T, and consequently move the feed-roller O in a similar direction to place a new block of wood P between the feed-rollers, 45 and then to hold the same in place.

50 The operation is as follows: When the knife-head C reciprocates and moves in the direction of the arrow a', then the knife H cuts with its edge on the under side of the block of wood P, as the said knife H is pressed upward by the spring K, acting on the arm J of the said knife H. When the knife-head C moves in this direction, the other knife H' is 55 pressed downward, as the cutting-edge of this knife stands in the opposite direction to that in which the head C moves, and consequently no cut or shaving is made by this knife. As soon as the knife-head C moves in the inverse direction of the arrow a' the cutting-edge of 60 the cutting-knife H' cuts a shaving from the

under side of the block P, while the other knife H is then depressed and does not cut. It will be seen that as the block of wood P is fed downward at each forward stroke of the 65 knife-head C, as previously described, the knife H will cut on this forward stroke, and when the cut is finished the block P is fed downward, so that on the return-stroke the knife H' can make its cut on the under side of the block. It will be seen that the block 70 of wood receives on its under side longitudinal cuts or slits from the cutters N, so that either knife H or H', instead of making a shaving the width of the block P, makes the shaving in strips, as the cutters are set apart 75 a distance corresponding to the width of the strip of excelsior to be cut. It is understood that the shaving-strips pass downward through the slots G and G', respectively. Any desired number of sets of knives H and H' 80 may be placed on one head or on a number of heads reciprocated by the same mechanism. By adjusting the screws L and L' the thickness of the cut—that is, the thickness of the excelsior—is regulated.

85 Instead of reciprocating the head C, the block P and its feed-rollers O and O' may be moved forward and backward, while the head C remains stationary. The action will be the same in both cases.

90 Having thus described our invention, what we claim as new, and desire to secure by Letters Patent, is—

1. In an excelsior-machine, the combination, with a reciprocating knife-head having 95 transverse slots and provided on its under side with lugs, of shafts held transversely on the said lugs, and knives inclined in opposite directions adapted to pass with their cutting-edges into the said transverse slots and provided with eyes engaging the said shafts, substantially as shown and described.

100 2. In an excelsior-machine, the combination, with a reciprocating knife-head having transverse slots and provided on its under side with lugs, of shafts held transversely on the said lugs, knives inclined in opposite directions adapted to pass with their cutting-edges into the said transverse slots and provided with eyes engaging the said shafts, arms 105 extending outward from the said knives, and springs pressing on the said arms to hold the cutting-edges of the said knives in the said slots above the top of the said knife-head, substantially as shown and described.
